UNITED STATES PATENT OFFICE

MESROB HOROFES, OF BUFFALO, NEW YORK

DESIGN FOR A SMOKER'S ASH RECEIVER

Application filed November 5, 1930. Serial No. 37,549. Term of patent 7 years.

To all whom it may concern:

Be it known that I, MESROB HOROFES, a citizen of the United States, residing at Buffalo, in the county of Erie and State of New York, have invented a new and original Design for a Smoker's Ash Receiver, of which the following is a specification, reference being had to the accompanying drawing, forming a part thereof.

Figures 1 and 2 are perspective views of the ash receiver embodying my design, taken from opposite sides thereof. Figure 3 is a top plan view of the receiver.

I claim:

The original design for a smoker's ash receiver, substantially as shown.

MESROB HOROFES.
